J. S. Gardner

ATTORNEY

UNITED STATES PATENT OFFICE.

HENRY A. DIRKES, OF NEW YORK, N. Y.

VENTILATOR.

979,134.

Specification of Letters Patent. Patented Dec. 20, 1910.

Application filed February 19, 1910. Serial No. 544,730.

To all whom it may concern:

Be it known that I, HENRY A. DIRKES, a citizen of the United States, and a resident of the city, county, and State of New York, 5 have invented certain Improvements in Ventilators, of which the following is a specification.

This invention relates to new and useful improvements in ventilators, and it has relation more particularly to that class of such devices which are intended to be employed in combination with the windows of buildings, cars and the like to allow vitiated or foul air to escape and it is an object of the 10 invention to provide a novel device of this character which is simple in construction, efficient and advantageous in practice and comparatively inexpensive to manufacture.

It is also an object of the invention to 15 provide a novel device of this character which is capable of ready application to windows or other openings without presenting an unsightly appearance and which, while facilitating the escape of vitiated or foul air, is adapted at the same time to effectually exclude the entrance of rain, dust, 20 or cold air and also to prevent drafts and damage as might be caused by such entrance.

The invention consists in certain features 25 of construction and in the novel arrangement and combination of parts to be hereinafter more particularly referred to and as illustrated in the drawings wherein like characters of reference denote corresponding 30 parts in the several views and in which—

Figure 1 is a view in elevation of the invention applied to a window. Fig. 2 is a 35 longitudinal sectional view of the invention taken on the line 2, 2 of Fig. 1. Fig. 40 3 is a sectional view taken on the line 3, 3 of Fig. 1, and Fig. 4 is a sectional view similar to Fig. 3 illustrating a modified form of the invention.

As illustrated in Figs. 1, 2, and 3 the invention is constructed from two slender elongated parts or members 1, 1 which overlap each other as clearly shown in Fig. 2 and which are fitted to slide one upon the other at the central portion of the device so that when the device is extended transversely across the upper part of the window, proper longitudinal adjustment of the said parts or members 1, 1, may be had in order to permit of accommodating the device to windows of different widths. Although these parts or members 1 are shown

on the drawings as formed from sheet metal, this is immaterial to the invention as wood or any other material desired may be substituted.

The ends of the parts or members 1 are closed by plates 2, 2, arranged at opposite ends of the device and as shown more particularly in Fig. 3 these end plates are adapted to receive attaching devices shown 60 herein in the form of screws 3, having engagement with the slotted openings 4, extended horizontally in inner edge portions of said end plates, the shanks of said screws being in engagement with the stiles of the 65 window casing 5, in such manner as to effectively support the improved ventilating device in position extended transversely across the windows.

The upper edge portions 6 of the parts 75 or members 1 are directed horizontally so as to be extended within the window casing 5 and said horizontally directed slotted openings 7, similar to the slotted openings 3 of the end plates 2 and these openings 7 are 80 adapted to receive screws or like fastenings 8 by means of which the device is adapted to be supported along its upper part upon the casing of the window or other opening to which it is applied.

As hereinbefore described, it is obvious that the device is supported in position extended transversely across the upper part of the window casing at the outer side thereof so as to stand in position to effectively shield 90 the opening produced across the top of the window casing when the upper sash is lowered and its upper rail 9 is separated from the top of the casing whereby it will be seen that the entrance of rain, snow, dust or the 95 like into the building is effectively prevented.

The inturned portions 6 of the parts or members 1 are free of contact with the opposed face of the casing 6 and thereby produce a port or vent 10 for the escape of the foul or vitiated air. This port or vent is maintained by the washers 11 surrounding the screws 8 as is particularly shown in Figs. 1 and 3. While it has been found most advantageous to employ the washers 11, it is to be stated that any other means capable of producing the desired result may be employed. The washers 11 are of a thickness equal to the height of the port or 100 vent 10 and thus assure the proper locking engagement of the screws 8 with the in-

turned portions 6 through the medium of the slots 7, as is believed to be apparent.

It is also within the scope of the invention that the end plates 2 be separated from the 5 adjacent sides of the casing 5 to produce ports or vents 12, (see Figs. 1 and 2), and this arrangement is provided by the washers 13 embracing the screws 3 and interposed between the opposing faces of the casing 5 and the end plates 2, said washers 13 being of such thickness as to assure the proper engagement of the screws 3 with the end plates 2 to assure the proper locking engagement. The members or parts 1 are also 15 provided with lower inturned portions 14 which are adapted to extend across the upper rail 9. At suitable locations intermediate their ends the parts or members 1 have pressed in the lower inturned portion 14 downwardly curved beads 15 which are intended to contact with the upper face of the rail 9 whereby the port or member 16 is produced between the lower inturned portions 14 and the opposed faces of the rail 9.

25 As shown in Figs. 1, 2, and 3 the device is approximately flush with the outer surface of the casing 5 and has the portion of the lower inturned portion crimped as at 17, to form a pendent portion. This provides a 30 means for preventing rain, snow or other moisture collected upon the device from entering the building. It is thought that as soon as the rain or moisture reaches the lowest point of the pendent portion 17, it 35 will run or drop therefrom.

The device is illustrated in Fig. 4 as constructed and applied in all essentials as the device shown by Figs. 1, 2 and 3, with the exception that the bead portion of each part 40 or member *a*, or that portion thereof which is downwardly extended across the upper part of the window opening adjacent to the top of the casing *b*, is downwardly and outwardly curved or inclined, as clearly shown 45 at *c*, so as to assure the rain, snow or the like falling thereon. Below the outwardly and downwardly curved bead portions *c*, the parts or members *a* are provided with deflecting surfaces *d* which are inclined 50 downwardly and inwardly toward the structure to which the device is applied and terminating in the crimped portion *e* for the same purpose as specified with the crimped portion 17 before referred to.

55 The end plates *g* are provided with projecting extensions or shields *h* which are outwardly and downwardly directed in such a manner as to prevent the entrance of sudden currents or cross drafts of air such as 60 might occasionally pass through the vent or port *i* formed by the lower portion of the device and the top rail *j* and thus interfere to an extent with the proper discharge of the foul or vitiated air.

35 From the foregoing description it will be

seen that the ventilator constructed according to my invention is of an extremely simple and comparatively inexpensive nature and is particularly well adapted for use by reason of the readiness and convenience with 70 which it may be installed and of the efficiency with which the foul or vitiated air is discharged without liability of entrance of rain, snow, dust or the like, or the production of drafts due to the entrance of external air 75 and it will also be apparent from the foregoing description that the device is susceptible of considerable change without material departure from the principles and spirit of the invention, and for this reason I do not 80 desire to be understood as limiting myself to the precise formation and arrangement of the several parts of the device as herein set forth in carrying out my invention in practice.

Having thus described my invention, what I claim and desire to secure by Letters Patent is:

1. A ventilating device comprising an elongated body portion, adapted to be extended across the upper part of a window, and having means for supporting it upon the window casing, and means for producing, when so positioned, an elongated narrow opening between one edge of the body 90 portion of the ventilator and the window casing to provide a port adapted for the discharge of air from the room.

2. A ventilating device comprising an elongated body portion adapted to be extended across the upper part of a window, and having means for supporting it upon the window casing, and means for producing, when so positioned, an elongated narrow opening between one longitudinal edge of 95 the body portion of the ventilator and the window casing to provide a port adapted for the discharge of air from the room.

3. A ventilating device comprising an elongated strip the upper edge portion of 110 which is directed inwardly from the central portion of the strip and is adapted to be extended along the upper end of a window opening or the like, said central portion being adapted, when the device is in position, 115 to be extended across the outer side of the window opening at the upper part thereof, said strip being also provided with a lower edge portion directed inwardly from said central portion and adapted to be located adjacent to but spaced from the upper sash rail to produce a narrow elongated opening for the discharge of air from said chamber.

4. A ventilating device comprising an elongated strip the upper edge portion of 120 which is adapted to be extended along the upper end of a window opening or the like, and the central part of which is inclined 125 downwardly and outwardly from the window, the lower part of said strip being a de-

flecting portion extended inwardly from said central portion and adapted to be spaced apart from the sash rail to produce an elongated opening for the discharge of air.

5. A ventilating device comprising an elongated strip the upper edge portion of which is adapted to be extended along the upper end of a window opening or the like, 10 and the central part of which is inclined downwardly and outwardly from the window, the lower part of said strip being a deflecting portion extended inwardly from said central portion and adapted to be spaced apart from the sash rail to produce 15 an elongated opening for the discharge of air and shields extended outwardly at opposite ends of the lower portion of said elongated strips and adapted to prevent the entry of air at the ends of said opening between said lower portion of the strip and the window sash.

6. A ventilating device comprising an elongated strip the upper edge portion of 25 which is directed inwardly from the central portion of the strip and is adapted to be extended along the upper edge of a window opening or the like, the lower portion of the strip being also directed inwardly and having 30 heads projecting therefrom to contact with the upper sash of the window to provide an elongated opening for the passage of air.

7. A ventilating device comprising an 35 elongated strip the upper and lower edge portion of which are deflected inwardly

from the central portion of the strip, the portion of the lower turned portion adjacent the central portion being provided with a depending crimp to prevent the passage 40 of moisture along the lower turned portion through the window opening or the like.

8. A ventilating device comprising an elongated body portion adapted to be extended across the upper part of a window and having means for supporting it upon the window casing when so positioned, and producing an elongated means for a narrow opening between one end edge of the body 50 portion of the ventilator and the window casing to produce a port adapted for the discharge of air from the room.

9. A ventilating device comprising an elongated body portion adapted to be extended across the upper part of a window and means for supporting it upon the window casing and means interposed between the casing and the body, when so positioned, for producing an elongated narrow opening 60 between one edge of the body portion of the ventilator and of the window casing to provide a port for the discharge of air from the room.

In witness whereof I have hereunto signed 65 my name this 31st day of January 1910, in the presence of two subscribing witnesses.

HENRY A. DIRKES.
